UNITED STATES PATENT OFFICE

SAMUEL C. CARNEY, OF TULSA, OKLAHOMA, ASSIGNOR TO SHELL PETROLEUM CORPORATION, A CORPORATION OF VIRGINIA

REFRIGERATING APPARATUS

Application filed December 7, 1925. Serial No. 73,851.

This invention relates to improvements in refrigerating apparatus and consists in the novel construction hereinafter disclosed.

An object of the present invention is to provide an apparatus whereby a refrigerant is kept in constant contact, largely in liquid form, with the inner surface of a rotating drum, said drum being mounted within a chamber in which the pressure may be reduced below atmospheric and to the outer periphery of which a supply of liquid to be frozen is conducted together with means for removing the liquid frozen on the periphery of the drum, whereby it may be packed into cakes for commercial purposes.

Generally stated, the invention consists of the novel construction, arrangement and combination of parts hereinafter described and the particular advantageous features of the structure will be readily recognized from the detailed disclosure thereof, taken in connection with the accompanying drawings in which

Fig. 1 is a vertical section through the apparatus;

Fig. 2 is a cross section; and

Fig. 3 is a detail view in vertical section of the mold for compacting and removing in cake form the frozen liquid produced by the apparatus.

Heretofore, in practice, in the manufacture of ice commercially there has been employed two general systems, namely, the can system and the plate system. In both of these, the heat from the liquid being frozen must be transmitted at a relatively low temperature difference through a considerable thickness of the frozen mass. Furthermore, in the can system and frequently in the plate system, heat from the water is transmitted first into the brine solution in which the liquid containers are submerged and then from the brine solution through the metal of the expansion or evaporating coils into the refrigerating liquid, thereby causing the evaporation of the liquid. In some plate systems, heat is transmitted directly through one thickness of metal from the water to the refrigerant, but the metal wall after a relatively short period of operation be-

comes covered with a thick coating of the frozen liquid, after which the heat is required to pass from the liquid to be frozen through a considerable thickness of the frozen mass, thus greatly reducing the effectiveness of the system as a whole.

Furthermore in the existing systems, the metallic surface of the pipe coil or the chamber in which the refrigerating liquid is being evaporated is, to a considerable extent, in contact with the vapor of the refrigerating liquid rather than with the liquid itself. Especially is this true in a long pipe coil, because the vapor of the liquid first evaporated must pass through the remaining length of the coil leading to the compressor or absorber. This results in a low coefficient of heat transmission, because a considerable part of the coil surface, namely, that part which is in contact only with the vapor on one side and with the brine solution or water on the other side, has an extremely low rate of heat transfer. Furthermore the brine solution or water in contact with the evaporating coils or chamber causes corrosion of the metal of the refrigerant container, thereby further reducing the rate of heat transfer.

The apparatus of the present invention overcomes the difficulties inherent in the present systems by freezing the liquids by means of heat transfer through a relatively thin metallic surface of high heat conductivity and removing the frozen bodies in a relatively small mass, thereby obtaining a high rate of heat transfer and a high efficiency from the refrigerant.

In the embodiment of the invention shown in the drawings, the foregoing results are accomplished by an apparatus comprising a housing which includes four segmental sections 1, 2, 3 and 4 respectively, having matching flanges 5 which are bolted together to form a chamber having substantially the cross sectional area illustrated (Fig. 2). The housing is supported by legs 6 for conveniently mounting it for operation. The ends of the housing are closed by end plates 7 and 8 which are bolted directly to flanges 9 formed at the ends of the segments, forming the body of the housing. The entire

housing is preferably exteriorly insulated by insulating material 10 covering the exposed surfaces thereof.

The castings forming the housing are joined together so as to form tight seals permitting a partial vacuum to be maintained therein. While the maintenance of a vacuum in the housing is not essential in all cases, it is generally preferable however for the purpose of removing air or other dissolved gases from the liquids being frozen. Furthermore, the vacuum acts as an insulating jacket preventing undue heat transfer from the exterior of the housing, and thereby maintaining the lowered temperature within the housing during the freezing operation.

The housing is therefore provided with a top opening 11 into which a pipe from a vacuum pump may be connected for the purpose of exhausting to the required degree the air from the housing and thereby to maintain a partial vacuum therein. The housing is also preferably equipped with sight openings 12 conveniently arranged so that the operation of the device may be observed. These sight openings are closed by transparent sight glasses 13, it being understood that it is preferable to construct the sight openings so that there will be heat insulation sufficient to avoid the rise of temperature above the desired internal temperature in the housing of approximately thirty-two degrees when ice is manufactured by the apparatus. If the apparatus is used for freezing other liquids, necessarily a corresponding internal temperature for freezing such liquid will be maintained.

A revolving drum is mounted within the housing, said drum comprising a cylindrical wall 14 preferably made of a relatively thin metal having a high heat conductivity. The ends of the drum are closed by end plates 15 which extend beyond the end of and are connected with the member 14 at opposite ends. The walls 15 are insulated by insulating material 16. The drum is supported for rotation in the housing by hollow shafts 17 and 18, said shafts being directly connected to the respective end plates 15 at the center thereof. Said shafts 17 and 18 communicate directly with the interior of the drum. They extend through the end plates 7 and 8, stuffing boxes 19 being provided to seal the openings through which said shafts extend. The shaft 17 is journaled in a bearing 20 supported by a bracket 21, said shaft carrying a pulley 22 by means of which the shaft and therefore the drum may be rotated from any suitable source of power.

The outer end of the shaft 17 is connected into a chamber 23, the opening through which the connection with the chamber 23 is made is sealed by a stuffing box 24. The

chamber 23 is supported by a bracket 25 in parallel alignment with the bracket 21 and has an outlet opening 26 into which a pipe leading to the refrigerant recovery system is connected.

The shaft 18 is supported in a bearing 27 carried by a bracket 28. The end of said shaft 18 carries a stuffing box 29 through which the refrigerant supply pipe 30 extends. A refrigerant supply pipe projects into the drum to a distance approximately midway of its length where it is turned approximately at right angles to form a nozzle 31, the opening of which is slightly below the scraping knife presently to be described.

A series of troughs are arranged around the interior wall of the drum, said troughs being composed of inwardly curved walls 32 connected at their outer end directly with the wall 14 and running longitudinally therewith. The walls 32 have upturned flanges 33 at their inner ends, said flanges being slightly spaced apart, thus forming a plurality of troughs with longitudinal openings in the center thereof running parallel with the axis of the drum. A series of pipes 34 extend from one trough to another, the connected troughs being approximately sixty degrees apart. By reference to Fig. 2 of the drawings, it will be noted that the pipes 34 connect alternate ones of the troughs which is a suitable arrangement for the number shown in the drawings.

From the description of the refrigerant supply pipe and the arrangement of the troughs with their cross connecting pipes, it will be understood that the original refrigerant supply discharged from the nozzle 31 is supplied to the troughs successively as they pass a point in their rotation slightly below the position of the scraping knife above referred to. Intercommunication between the troughs is provided for by perforating the walls 32 along a line of their juncture with the wall surfaces 14 and indicated on the drawings by the numeral 35; and also by the pipes 34.

The result of this arrangement is that the entire internal surface of the drum except a segment of approximately ninety degrees of the circumference positioned at the top of the drum during its rotation will be subjected to a continuous bath of the refrigerating liquid. The relatively large open space in the central portion of the drum provides a chamber into which the vapor of the refrigerating liquid escapes.

In operation, the refrigerant is first poured into the troughs on the descending part of the revolution and there is also poured into the descending troughs through the cross connecting pipes 34 refrigerant which has not leaked out through the perforations 35 on the ascending part of the

revolution. The lower part of the rotating drum carries at all times a reasonably large supply of refrigerating liquid which is continuously replenished through pipe 30 and is picked up by the troughs as they successively pass the lowest point in their revolution for distribution to the ascending part of the drum surface by leakage through perforations 35 and for transfer through pipes 34 from the troughs completing the ascending part of the revolution to those beginning the descent.

Extending longitudinally of the housing are two supply pipes 36 and 37, the supply pipe 36 being arranged near the top of the housing and in a plane approximately passing vertically through the axis of the drum 14. The pipe 36 is blanked against one end of the drum at 38 and extends outwardly through a stuffing box 39 at the opposite end, it being understood that the pipe is externally connected with the source of supply of the liquid to be frozen which preferably is supplied to the pipe 36 in a pre-cooled condition. The pipe 36 is perforated throughout the length thereof that extends within the housing and should be preferably made adjustable in a rotary direction so that the incoming liquid may be sprayed against the surface of the drum 14 so that it will flow in both directions over the drum surface.

The liquid flowing in the direction of rotation of the drum (Fig. 2) serves to bathe the scraping knife edge, and the frozen mass that is scraped from the periphery of the drum by the knife. Part of the liquid flowing in the reverse direction of rotation of the drum will be frozen but a sufficient amount should be supplied in order to provide an excess to bathe off the air bubbles from the portion that is frozen. Any excess liquid flowing in either direction accumulates in the bottom of the housing. The pipe 37 extends longitudinally of the drum 14, it being understood that the arrangement of the inner end of the pipe is the same as that described in connection with the pipe 36 and that the pipe 37 also extends outwardly through the end plate through a stuffing box (not shown). In other words, the arrangement of the pipe 37 and its mounting is identical with the mounting for the pipe 36, the pipe 37 however being positioned just below the scraping knife.

The liquid from the pipe 37 is discharged against the drum in the direction of its rotation and the liquid should be applied with sufficient force to cause a considerable velocity relative to the surface of the drum, spraying a relatively thin film of liquid against the drum periphery which readily freezes due to the fact that the wall 14 has a very high heat conductivity and the heat

from the liquid is rapidly withdrawn by the action of the refrigerant in the drum. The excess liquid accumulates in the bottom of the housing and where a liquid such as raw water is used, it is preferable to continuously withdraw the water from the bottom of the housing to prevent concentration of impurities. The excess liquid is withdrawn through any suitable form of discharge pipe (not shown) which may be controlled by an automatic level control 40 and the level of the water may or may not be in contact with the lower periphery of the drum. In any event it should not rise to any considerable extent above the lower segment of the drum.

The accumulated excess of the liquid in the bottom of the housing will be maintained at a temperature closely approximating the freezing point of the liquid. The temperature may be regulated by controlling the amount of excess supplied through the supply pipes. The excess accumulation of liquid in the housing serves to regulate the temperature in addition to its function in eliminating the air bubbles during the freezing operation. The liquid withdrawn from the housing by suitable means may be used for reintroduction into the apparatus through the supply pipes.

The accumulated congealed layer of the liquid that is formed upon the periphery of the drum is scraped off and removed therefrom by a scraping knife 41 set at a tangent to the periphery of the drum and extending outwardly therefrom in the direction of its rotation. The scraping knife extends the full length of the drum and is carried by a rod 42 that extends outwardly through a stuffing box 43 in the wall of the housing and is adjustable by a hand wheel 44 so as to regulate the contact of the edge of the knife with the periphery of the drum.

As the frozen liquid is scraped from the drum by the scraping knife 41, it is deflected into a rectangular mold comprising a bottom wall 45 and side walls 46 and 47, said walls extending longitudinally of the housing within the segment 3 and outwardly for some distance beyond one end of the housing as clearly illustrated in Fig. 3. The side wall 46 has an outwardly extending wall substantially in the plane tangential to the periphery of the drum, the outer edge of which is near the outer edge of the knife blade and serves to catch and deflect the separated frozen particles into the mold.

The mold is formed with a cover in two sections, the section 48 which covers the mold exteriorly of the housing being permanently set or rigid with the side walls so as to form a rectangular compartment having an open end. The portion of the cover within the housing comprises a sliding plate 49 that is arranged to slide outwardly into a closed housing 50. The entire mold, in-

cluding the cover section, is made of heavy metal capable of withstanding sufficient internal pressure to compact the small particles or flakes of the frozen liquid entering the mold. The interior of the mold is machined and ground smooth and the movable section of the cover is machined and ground on all surfaces so that it may be easily reciprocated to open and close the section 10 of the mold within the housing.

A follower head 51 is mounted to reciprocate within the portion of the mold cavity within the housing of the apparatus. The follower head 51 is operated by a piston construction including a piston rod 52 that extends through a stuffing box 53 in the end wall of the housing being connected directly to the follower head 51 at its inner end. The piston rod extends through a stuffing box 54 in the end of a piston cylinder 55 mounted exteriorly of the housing of the apparatus. A piston 56 is mounted in the piston cylinder and is arranged to reciprocate in the piston to move the follower head 25 under force forwardly in the mold cavity and to return the follower head to the position shown in Fig. 3 after it has served to compress the frozen particles accumulated in the mold.

30 The discharge end of the mold is fitted with a similar close-fitting follower head 57 which is operated in the same manner and controlled to move in a direction opposite to the follower head 51 so that by the opposite movement of the follower heads 51 and 57, the separated particles or frozen bodies will be compressed, after which the follower head 57 may be withdrawn from the discharge end of the mold and by moving the follower head 51 forward, the compacted frozen body in the form of a cake may be moved out of the mold. It is preferable that some degree of heat should be applied to the exterior portion of the mold to prevent the cake from adhering to the side walls and to facilitate the removal thereof.

35 The movable section 49 of the cover is adapted to be reciprocated by means of a rod 58 that extends outwardly through a stuffing box 59 in the end of the housing of the apparatus. This rod 58 extends into a piston cylinder 60 through a stuffing box 61, said rod carrying at its end a piston 62 which piston is double-acting for moving 55 the cover section 49 into a position to cover the mold and to a position exterior of the housing of the apparatus to uncover the mold.

40 It will be understood that the particles or frozen bodies scraped from the drum are accumulated in the interior section of the mold when the cover section 49 is withdrawn from the top thereof. The cover section is then moved to cover the mold and the follower heads are operated as above described

for compressing and removing the accumulated body of the frozen liquid.

During the period that the cake is being formed, the frozen particles are accumulated on the top of the cover section 49 and when the mold is reset for receiving the accumulation by withdrawing the cover section 49, that part of the frozen liquid that has accumulated upon the upperface of the cover section will fall into the mold. The operation of forming the cakes may be repeated as a continuous operation.

45 It will be noted that the mold is separated from the housing by a baffle wall 63 but that there is a port 64 in the baffle wall so that a portion of the mold will be submerged in the excess liquid in the bottom of the housing, serving to maintain the walls of the mold at a temperature under which the separated particles or frozen bodies may be 50 readily compacted and sufficiently high to prevent the adherence of the frozen cake to the walls of the mold.

55 While I have described in some detail the construction of the mold as a convenient way of forming cakes of the frozen liquid, the specific construction of the mold is not part of the invention and is only one way of removing the frozen bodies from the apparatus. The mold may be dispensed with 60 and the frozen bodies scraped from the drum may be discharged directly into the excess liquid in the bottom of the housing and removed therefrom by a continuous conveyor fitted to the housing, said conveyor being of 65 the form and type described and disclosed in my copending application Serial No. 59,796.

60 It is contemplated that the supply of refrigerant may be conveniently controlled 70 automatically by a thermostat device, the control element of which may be placed in the vapor discharge conduit and that if desired the liquid supply may be also automatically controlled by suitable thermostat 75 devices, the control elements of which may be subjected to the influence of the internal temperature of the housing of the apparatus.

75 It is contemplated that the apparatus may be supplied with any suitable liquid refrigerant, it being preferred, however, that a hydrocarbon refrigerant be utilized.

80 I am aware that the construction of the apparatus may be modified in numerous particulars without departing from the spirit and scope of the invention. For example, if desired, the wall of the drum may be made corrugated to increase the effective surface thereof without increasing the dimensions. It is also contemplated that the arrangement 85 of internal cross connected troughs of the drum may be dispensed with and that the liquid refrigerant may be directly supplied to the interior of the drum and by varying the speed of rotation thereof by centrifugal 90 force.

action, the liquid may be kept in contact with the drum surfaces.

It will be understood that the speed of rotation of the drum may be regulated to control the refrigerating action of the apparatus.

What I claim and desire to secure by Letters Patent is:

1. In a refrigerating apparatus, the combination of a hermetically sealed housing, a hollow drum adapted to be rotated in the housing, means for admitting a liquid refrigerant to the interior of said drum, means for maintaining a relatively small amount of liquid refrigerant against a relatively large area of the interior wall of the drum, means for admitting a liquid to be frozen to the exterior of said drum, means for removing the frozen liquid from the exterior of the drum, and means for compacting and removing the frozen liquid in cake form from said housing.

2. In a refrigerating apparatus, the combination with a housing of a rotary drum mounted therein, means for admitting liquid refrigerant to the interior of said drum, internal troughs supported by the wall of said drum and adapted to deflect the liquid refrigerant against the inner periphery of the drum, and means for admitting liquid to the exterior of said drum.

3. In a refrigerating apparatus, the combination with a housing of a rotary drum mounted therein, internal troughs supported by the wall of said drum, means for admitting liquid refrigerant to the interior of said drum, said liquid being distributed against the inner periphery of the drum by said troughs, and means for admitting liquid to the exterior of said drum, said troughs being arranged for intercommunication.

4. In a refrigerating apparatus, a sealed heat insulated housing, a hollow drum arranged to rotate within the housing, an axial supply pipe adapted to admit a liquid refrigerant to the interior of said drum, an axial pipe at the opposite end of said drum adapted to withdraw the expanded vapors from the drum, a series of internal communicating troughs arranged to distribute the liquid within the drum against the inner periphery thereof, a liquid supply pipe arranged above the drum and having a series of discharge nozzles for discharging liquid against said drum, and an adjustable knife adapted to remove the layer of ice formed on the drum.

5. In a refrigerating apparatus, an hermetically sealed chamber, a rotary drum within said chamber, means for admitting a refrigerant to the interior of said drum, a spray device for spraying liquid on the exterior of said drum, a partition in said drum constituting a trap for the liquid in the bottom of the chamber, a scraping device ar-

ranged to remove the liquid congealed on said drum, an adjusting device operable exteriorly of the housing for adjusting said scraping device, and means located within the housing for confining and compacting 70 the congealed liquid scraped from the drum.

6. In a refrigerating apparatus, an hermetically sealed chamber, a rotary drum within said chamber, means for admitting a refrigerant to the interior of said drum, a spray device for spraying liquid on the exterior of said drum, a partition in said drum constituting a trap for the liquid in the bottom of the chamber, a scraping device arranged to remove the liquid congealed on 80 said drum, and means located within the housing for confining and compacting the congealed liquid scraped from the drum.

7. In a refrigerating apparatus, an hermetically sealed chamber, a rotary drum 85 within said chamber, means for admitting a refrigerant to the interior of said drum, a spray device for spraying liquid on the exterior of said drum, a partition in said drum constituting a trap for the liquid in the bottom of the chamber, a scraping device arranged to remove the liquid congealed on 90 said drum, and a mold located within the housing near the bottom thereof for receiving and compacting the frozen liquid scraped 95 from the drum.

8. In a refrigerating apparatus, an hermetically sealed chamber, a rotary drum within said chamber, means for admitting a refrigerant to the interior of said drum, 100 a spray device for spraying liquid on the exterior of said drum, a partition in said drum constituting a trap for the liquid in the bottom of the chamber, a scraping device arranged to remove the liquid congealed on 105 said drum, a mold located within the housing near the bottom thereof for receiving and compacting the frozen liquid scraped from the drum, and means for controlling the liquid level in the bottom of said drum. 110
